(57) **CLAIM**

The ornamental design for a manifold for a fire extinguishing system, as shown and described.

DESCRIPTION

This application is related to Applicant's co-pending U.S. application Ser. No. 17/138,244, titled Fire Extinguisher Manifold, filed on Dec. 30, 2020, the disclosure of which is hereby incorporated by reference in its entirety.

FIG. 1 is a perspective view of a first embodiment of a manifold for a fire extinguishing system.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a front perspective view of a second embodiment of a manifold for a fire extinguishing system.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines in the Figures depict portions of the manifold for a fire extinguishing system that form no part of the claimed design. The area between the sets of wavy broken lines in FIGS. 8-10 and 13-14 forms no part of the claimed design.
